UNITED STATES PATENT OFFICE.

FREDERICK M. FURBER, OF BEACHMONT, MASSACHUSETTS, ASSIGNOR TO UNITED SHOE MACHINERY COMPANY, OF PATERSON, NEW JERSEY, A CORPORATION OF NEW JERSEY.

FLEXIBLE OUTSOLE.

1,115,922.

Specification of Letters Patent.

Patented Nov. 3, 1914.

Application filed December 16, 1912. Serial No. 736,997.

To all whom it may concern:

Be it known that I, FREDERICK M. FURBER, citizen of the United States, residing at Beachmont, in the county of Suffolk and 5 State of Massachusetts, have invented certain new and useful Improvements in Flexible Outsoles; and I do hereby declare the following to be a full, clear, and exact description of the invention, such as will enable others skilled in the art to which it 10 appertains to make and use the same.

This invention relates to soles for boots and shoes and more particularly to flexible outsoles.

15 Some trouble has been experienced in having boots and shoes rip in the shank portion and this is due, to some extent to the stiffness of the outsole. In securing the outsole to the shoe it is drawn up in an arch at the 20 inside of the shank and owing to its tendency to straighten out exerts a continual pull on the line of stitches which in time, from this and additional causes, rip.

The object of the present invention is to 25 produce an outsole that will retain its arched shape at the inside of the shank and thus relieve the strain on the stitches.

With this object in view it is contemplated 30 to provide the outsole with a flexible shank at the inside, and while this may be accomplished in several ways, it is proposed to provide the inside of the shank, on the flesh side of the sole, with one or more cuts or slits 35 permitting this portion of the shank to give or flex as it is arched when the sole is applied to the shoe. In the preferred form of the invention the cuts or slits comprise a series of transverse, marginal slashes.

To the accomplishment of this object the 40 invention comprises the novel, flexible outsole hereinafter described and defined in the appended claims.

In the accompanying drawing, showing the best form of the invention at present 45 known, Figure 1 is a plan, showing the flesh side of the outsole, Fig. 2 is view showing the novel outsole as applied to a shoe, which is shown in dotted lines and Fig. 3 is a cross-section on the line 3-3 of Fig. 2.

In the illustrated embodiment of the invention the outsole *a*, which may be a dinked-out sole as shown or may be any other commercial form of outsole, is provided on its flesh side with a series of transverse, marginal slashes *b* located, at the in-

side of the shank between the breast line and ball line. These slashes preferably radiate from the edge of the sole and cover a sufficient area to permit a free arching of the shank. In practice it has been found that 60 about twenty slashes, about seven eighths of an inch long and spaced about one-eighth of an inch apart give excellent results. The slashes are made to extend but part way through the outsole, as the grain side must 65 not be injured, although their depth is sufficient to sever the fiber of the leather in the fleshy surface of the sole. Owing to the fact that the arch at the inside of the shank merges into a substantially straight line at 70 the outside of the shank the necessity for flexibility decreases as the center of the shank is approached. It is therefore preferred, in order to obtain a better set of the outsole on the outside shank and so as not 75 to unduly weaken the outsole, to decrease the depth of the cut from *c* to *d* as shown in Fig. 3. When the outsole is sewed in place the opening of the slashes *b*, as shown in Fig. 2, readily permit the necessary bending 80 at the shank and afford sufficient flexibility to overcome the strain present in the stiff shanks of ordinary outsoles.

While in the illustrated form of the invention the cuts or slits *b* are shown as extending to the inside edge of the outsole, this is not essential in practising the invention as the importance of the cutting of the outsole resides in such treatment of the sole as will make its margin at the inside shank 90 flexible and not in the particular form or position of the cuts.

The nature and scope of the present invention having been indicated and the preferred embodiment of the invention having been 95 specifically described, what is claimed as new, is:—

1. As an article of manufacture, a flexible outsole for boots and shoes having one or more cuts or slits in its flesh side at the inside of the central portion of the shank only, leaving the outside of the shank uncut, substantially as described.

2. As an article of manufacture, a flexible outsole for boots and shoes having a series 100 of transverse slashes in its flesh side at the shank extending from the inner edge of the sole part way across the width of the shank and part way through its thickness, substantially as described.

3. As an article of manufacture, a flexible outsole for boots and shoes having a series of transverse marginal slashes in its flesh side at the inside of the shank said slashes extending part way across the width of the shank and part way through the thickness of the sole and being of less depth at their inner ends than at their outer ends, substantially as described.
- 10 4. As an article of manufacture, a flexible

outsole for boots and shoes having a series of transverse slashes in its flesh side at the shank arranged radially with respect to the curvature of the edge of the shank, substantially as described.

FREDERICK M. FURBER.
